UNITED STATES PATENT OFFICE

HARRY L. FINK, OF NEW YORK, N. Y.

FLOOR SURFACING MACHINE

Application filed May 21, 1928. Serial No. 279,229.

My invention relates to floor surfacing machines of the class usually employed for grinding or "finishing" terrazzo mosaic, marble or composition floors.

Especially the invention relates to the construction and arrangement of supporting and traversing wheels for such machines.

The general object is to provide two distinct and separately-revolvble wheels, mounted on a single axle, having conoidal, or mutually-crowned tread-surfaces, and so arranged as to constitute (except for the grinding surfaces or "stones") the entire support of the machine, by which it may be properly traversed over the floor surface, swing or tilted laterally, or easily rolled while the grinders are held in elevated position and inactive, without necessity for any additional or auxiliary supporting wheels or rollers.

The characteristics and advantages of the invention are further sufficiently explained in connection with the following detail description of the accompanying drawings, which show one preferred embodiment. After considering this example, skilled persons will understand that many variations may be made, and I contemplate the employment of any structures that are properly within the scope of the appended claims.

Fig. 1 is a side elevation of a machine embodying the invention in one form.

Fig. 2 is a section at 2—2, Fig. 1.

Fig. 3 is a front elevation, on reduced scale.

The frame 1 supports near its rear end the motor 2, and at its front end, housings 3, 4 and 5, enclosing, respectively, gearing, vertical shafts, and the grinding head supporting the grinders proper, or stones 6. In some cases there may be only one grinder. The motor is connected to the gearing by shafts and a flexible coupling 7. Handle struts 8 are connected to the rear end of the frame.

The entire support of the machine (aside from the grinders) is provided by two wheels 10, mounted for independent rotation on an axle 11. This axle is secured by caps 12 and screws or bolts 13 to the ends of lugs or brackets 14 which depend from the frame sides, and may be integral therewith. The axle 11 is preferably located somewhat forward of

the center of gravity of the motor, but substantially back of the grinders and housings 3, 4 and 5, so that the natural gravity balance of the machine will apply sufficient pressure to the stones, and at the same time the rearward overhang of the motor permits the machine to be tilted upon the wheels, to elevate the stones, without undue effort of the operator.

The wheels are slightly spaced apart, and are arranged substantially in longitudinal alignment with the grinders, when two grinders are provided, or when there is only one grinder, its axis intersects the longitudinal central axis of the machine, which also intersects axle 11 between the two wheels.

The wheel thread-surfaces 15 are moderately rounded, conoidal, or mutually "crowned", the portions of largest diameter being located inward and adjacent each other; and the immediately-adjacent portions of the threads are more abruptly rounded off, as at 16, to avoid any sharp edges which might score the floor surface.

To provide for easy movement of the machine, the wheels are preferably mounted on anti-friction bearings. In the present specific example, these are roller bearings, including rollers 20 running between the axle and wheel races 21, and held in place by end plates 22, with thrust or spacing washers 23 interposed between the plates and brackets 14, when desired. The central spacing of the wheels is maintained by a plate 24, one end of which is located in or secured to the frame as at 25, and the other end is apertured to receive and surround the axle, and act as a spacer between the inward plates 22. This plate 24 also acts as a guard or scraper, preventing accumulation of ground-dust or other débris, which would otherwise tend to clog the wheels, or to cause them to rotate together, which is undesirable in certain maneuvers, as will appear from the following explanation of operation:

While grinding, the machine is pushed forward and backward with comparative ease by reason of the anti-friction wheel bearings. The lateral balance of the machine is easily maintained because of the wide combined

- tread of the two broad wheels; but at the same time the machine is easily tilted in its transverse vertical plane, either by floor-in-
5 equalities acting upon the grinders, or in-
tentionally by the operator to properly grind off "high spots", the rearward part of the machine in such tilting, rocking upon the wide arcuate lateral support afforded by the mutual crown or curvature of the wheel
10 treads. The machine is also easily swung laterally, in the horizontal plane, to sweep the grinders over desired zones of the floor surface, because of the independent revoluble mounting of the wheels, which may revolve
15 at any necessary different speeds in the same or opposite directions, to freely permit such swinging.

When it is desired to raise the grinders out of contact with the floor, this is easily ac-
20 complished by downward pressure upon the handles, the machine frame then pivoting at the axle center, because of the location of the axle at a favorable point in relation to the longitudinal center of gravity, as above
25 referred to, and without necessity for any additional or auxiliary wheels or rollers to support the machine in this position, such as have heretofore been necessary in certain ma-
chines of this general class.

30 I claim:

1. In a floor-surfacing machine, in combi-
nation with the frame, motor and one or more grinders, and two supporting and traversing wheels independently-revolubly mounted on
35 a common axis, the wheels being substantially spaced apart and means located between them to prevent accumulation of débris and clogging.
2. In a floor-surfacing machine, in combi-
40 nation with the frame, motor and one or more grinders, and two supporting and traversing wheels independently-revolubly mounted on a common axis, and a scraper plate located between the wheels.

45 In testimony whereof I affix my signature.

HARRY L. FINK.
